UNITED STATES PATENT OFFICE.

CHARLES J. PHILLIPS, OF SPENCER, IOWA.

GRAIN-DOOR FOR BOX-CARS.

1,330,031.

Specification of Letters Patent. Patented Feb. 3, 1920.

Application filed August 19, 1918. Serial No. 250,487.

To all whom it may concern:

Be it known that I, CHARLES J. PHILLIPS, a citizen of the United States, and a resident of Spencer, in the county of Clay and State of Iowa, have invented a certain new and useful Grain-Door for Box-Cars, of which the following is a specification.

The object of my invention is to provide a grain door, preferably of metal, of simple construction which can be used when the car is loaded with grain and will afford a grain tight joint, allowing proper and easy access to the interior of the car when that is necessary.

With this and other objects in view my invention consists in the construction, arrangement and combination of the various parts of the device, whereby the objects contemplated are attained, as hereinafter more fully set forth, pointed out in my claims, and illustrated in the accompanying drawings, in which:

Figure 1 shows an elevation of the grain door, viewed from the inside of the car.

Fig. 2 shows a vertical, sectional view taken on the line 2—2 of Fig. 1.

Fig. 3 shows a vertical, sectional view taken on the line 3—3 of Fig. 1.

Fig. 4 shows a vertical, sectional view taken on the line 4—4 of Fig. 1.

Fig. 5 shows a horizontal, sectional view taken on the line 5—5 of Fig. 2.

Fig. 6 shows a horizontal, sectional view taken on the line 6—6 of Fig. 1.

Fig. 7 shows a view taken on the line 7—7 of Fig. 6.

Fig. 8 shows a vertical, sectional view taken on the line 8—8 of Fig. 1; and

Fig. 9 shows a vertical, sectional view taken on the line 9—9 of Fig. 1.

In the accompanying drawings I have used the reference numeral 10 to indicate generally the floor of a box car which has the outside wall 11, with the ordinary door opening with the upright door frame posts 12 and 13.

I have shown also at the top of the car 14 a diagonal brace 15. Outside the car the ordinary sliding door, not here shown, and forming no part of my invention is used. My improved grain door is made in three sections superimposed one above the other, and I will now describe the lower section.

The lower door section comprises a door member 16 which slides in a groove 17, indicated by dotted lines in Fig. 1, in the floor

10 of the car, from its position for closing the door opening to position received in the car on the inside of the outer wall thereof.

The following means are provided for supporting the door section 16 for sliding it:

At the upper end of the door section 16 is provided an outwardly extending strip or member 18 having at its outer end a downwardly extending flange 20. Spaced longitudinally along the car side from the upright post 13 is a small post 21 shown by dotted lines in Fig. 1. The posts 12, 13 and 21 are provided with several series of horizontally aligned transverse slots or recesses 22.

One series of the recesses 22 is arranged in a horizontal line substantially on a line with the upper edge of the lower door section 16. In each of the recesses 22 is mounted a suitable bracket 23 having a pair of bearings 24. In each pair of bearings is mounted a shaft 25. On each shaft 25 near its outer end is a roller 26 and spaced inwardly from the roller 26 is a roller 27 on which travels the outwardly extending member 18 of the door section 16.

The roller 27 is formed with a reduced portion 28 at its outer end on which travels the flange 20, as illustrated in Fig. 2. It will thus be seen that the door section 16 may slide freely on the roller 27 from its closed position, shown in Fig. 1, to its position on the inside of the car. The door section 16 is provided in its lower central portion with a suitable opening 29, indicated by dotted lines in Fig. 1.

A suitable small sliding unloading door 30 is provided for covering the opening 29. The door 30 is arranged to slide on the inside of the door section 16 between suitable upright guides 31, illustrated particularly in Figs. 1, 4 and 8.

On the outer surface of the lower part of the door 30 is a slot or recess 32 for permitting the door 30 to be raised in its guides by a crow bar or otherwise.

Secured to the outer surface of the door section 16 is a spring clip device 33, shown in Figs. 3 and 1, which has on its free end a pin 34. One end of the spring clip device 33 is pivotally mounted on the door section 16, so that said clip may swing laterally.

The door section 16 is provided with an opening to permit the insertion of the pin 34 through said door section, so that when the discharge or unloading door 30 is in its

loading position, the pin 34 will stand just above the door 13 and prevent the raising thereof.

The slot 17 is wide enough below the door 30 to permit the lower edge of the door 30 to be received in said slot.

When it is desired to open the door 30 when the car is loaded, the operator holds the lower end of the spring clip 33 outwardly withdrawing the pin 34 from the opening therefor in the door section 16, and preferably swings the clip 33 laterally somewhat, as illustrated by dotted lines in Fig. 1, so that the pin can then not reenter its opening in the door section 16.

The door 30 is then raised by means of a crow bar or the like and the grain can flow out below the door 30.

Near one upright edge of the door section 16 there is provided a suitable locking device.

Spaced laterally from the upright member 12 and from the door opening in the car side is another upright studding or frame member 35.

Secured to the inner surface of the upright member 35 is a strip 36 which projects inwardly into the car at 37, and thence longitudinally along the car as at 38 for forming a keeper for the edge of the door sections.

Secured to the strip 36 is one end of a catch device 39 which extends through the portion 37 of the clip 36 and terminates in a catch 40, which is designed to enter and coact with a suitable recess 41 in the outer surface of the door section 16.

The main portion of the catch device just described is made of resilient material.

For operating the catch device for discharging the car, there is provided a slide rod 42 slidably extended through the side of the car, having at its outer end a ring 43, and having its inner end pivoted to the catch member 39.

In the use of the door section 16, assume that said section is closed and it is desired to take the grain out through the door opening therein, the operator pulls the lower end of the spring device 33 outwardly until the pin 34 releases the discharge door 30, whereupon that door may be raised. When the door 30 is closed it may be locked in position by means of the pin 34.

If it is desired to open the door section 16, the operator grasps the ring 43, pulls the slide rod 42 outwardly for releasing the catch 40 from engagement with the notch 41, whereupon the door 16 may be slid alongside the car on the interior thereof and opened.

Above the door section 16 is a door section 44, and above the door section 44 is a door section 45 similarly constructed.

It is thought that a description of the door

section 44 will be sufficient to describe both sections 44 and 45.

The door section 44 is arranged so that its lower edge overlaps the door section 16 on the side thereof, as illustrated in Figs. 2 and 9. Near its lower edge there is secured to the outer surface of the door section 44 an outwardly extending strip 46, which, at its outer end, terminates in a downwardly extending flange 47 which travels on the rollers 26 on one horizontal series of said rollers.

At the upper edge of said door section 44 is an outwardly extending member 18^a similar to the member 18 and terminating in a downwardly extending flange 20^a similar to the flange 20 which travels on the reduced portion 28 of one horizontal series of the rollers 27.

The door sections 44 and 45 are provided with locking devices similar to that already described for the door section 16.

On the outer surface of each door section is a pivoted handle 49. On the inside of the car there is provided spaced inwardly from the upright posts, hereinbefore mentioned, a grain shield 50 which terminates above the bottom of the car so that if any grain should work behind the shield it would drop out the bottom of the shield when the load of grain is removed from the car.

In the practical use of my improved grain door, it will be understood that ordinarily the door section 45 will be left open, and the door sections 44 and 16 closed while the car is being loaded, and when the car is loaded the door section 45 will be closed.

When the car is unloaded the door section 45 may be opened by sliding it alongside the car to position behind the shield 50 and a spike inserted, or if desired, the car may be unloaded by opening the door 30. When my improved grain door is not in use or when the car is used for purposes other than hauling grain, the door sections 16, 44 and 45 are slid to position behind the shield 50 and the side of the car where they will not be injured by the contents of the car.

It will be noted that the arrangement of the flange 20 with the large part of the roller 27 prevents any inner movement of the door sections at the upper portion thereof; and that the flange 20 serves to prevent any inner movement of the lower door section on account of the fact that the flange 20 stands in the path of the flange 47 for preventing any such inner movement.

Some changes may be made in the construction and arrangement of the parts of my improved grain door without departing from the essential features and purposes thereof, and it is my intention to cover by my claims any modified forms of structure or use of mechanical equivalents which may be reasonably included within their scope.

I claim as my invention:

1. The combination of a car having a side wall with an opening therein, and having inside said wall upright posts with horizontally alined inwardly opening recesses therein, a plurality of door sections arranged in vertical succession having outwardly extending flanges at their horizontal edges, and downwardly extending flanges at the outer edge of the first described flanges, whereby said flanges may be received in said recesses to permit horizontal reciprocation of the sections relative to each other and to the posts and movement in other directions may be limited.

2. The combination of a car having a side wall with an opening therein, and having inside said wall upright posts provided with transverse recesses, guide rollers in said recesses, a pair of door sections arranged one above the other and arranged to slide from

position for closing said door opening to position alongside the interior of the car adjacent to said upright posts, part of said guide rollers having reduced portions, said door sections having inwardly extending members provided with downwardly extending flanges adapted to rest on said reduced portions and to be held against inner movement in the wall by the larger portions of the guide rollers which have the reduced portions, said door sections being arranged one above the other with the lower end of the upper section overlapping the upper end of the lower section, and an outwardly extending member near the lower edge of the upper section resting above the outwardly extending member of the lower door section, and having at its outer end a downwardly extending flange adapted to rest on some of said rollers.

Des Moines, Iowa, July 24, 1918.

CHARLES J. PHILLIPS.
